UNITED STATES PATENT OFFICE.

ALEXANDER W. MOREY, OF TROY, NEW YORK.

BRUSH-MAKING MACHINE.

1,162,639.

Specification of Letters Patent. Patented Nov. 30, 1915.

Application filed December 15, 1914. Serial No. 877,390.

To all whom it may concern:

Be it known that I, ALEXANDER W. MOREY, a citizen of the United States, residing at Troy, in the county of Rensselaer and State 5 of New York, have invented new and useful Improvements in Brush-Making Machines, of which the following is a specification.

An object of the invention is to provide 10 a machine for making brushes and daubers, such as are used in polishing shoes, making stencils, for painting or cleaning purposes and the like.

The invention contemplates, among other 15 features, the provision of a machine for quickly and without danger to the operator, securing the usual bristles in a holder and whereby they will be held firmly therein, a suitable plug being provided for the 20 purpose and which, forced into the holder, will securely hold the bristles of the brush body therein.

In the further disclosure of the invention 25 reference is to be had to the accompanying drawings, constituting a part of this specification, in which similar characters of reference denote corresponding parts in all the views, and in which:

Figure 1 is a fragmentary perspective 30 view, the device being shown in position for advancing a plug into a holder; Fig. 2 is a similar view, showing the plug about to be secured in the holder, the brush body being shown in section; Fig. 3 is a vertical 35 sectional view taken through the device for advancing the leader and plug into the brush body; Fig. 4 is a horizontal sectional view taken on the line 4—4 in Fig. 2; and Fig. 5 is a perspective view of the member 40 for supporting the leader and plug.

Referring more particularly to the views, I disclose a driver 10 in the nature of a rod and which is adapted to be actuated by suitable hand or mechanical power to slide 45 through a supporting member 11 in the nature of a sleeve and which is preferably provided with a vertical slot 12 with a stop pin 13 carried by the driver 10 and operating in the slot 12 to limit the sliding movement 50 of the driver with respect to the supporting member 11. The driver 10 carries a collar 14 and the supporting member 11 is formed with a collar 15, an expansible helical spring 16 being arranged to loosely encircle the driver 10 and abut against the mentioned collars 14 and 15 whereby the

supporting member will normally be at the lowermost end of the driver, said supporting member being held upon the driver by the stop pin 13 engaging the collar 15 of 60 the supporting member, as shown.

The supporting member is preferably tapered and includes a plurality of depending spring-like gripping members 17 which, on account of the taper of the supporting 65 member, converge, said gripping members extending downwardly below the lower end of the supporting member to receive and support a plug 18 and a leader 19 carried in advance of and below the plug 18. A 70 projection 20 extends horizontally from the collar 15 and is adapted to engage a substantially angular member 21 arranged in juxtaposition to the supporting member 11, said projection only coming in contact with 75 said member 21 when the driver 10 is forced downwardly and when so operated, causing the supporting member 11 to be brought to a stationary position and prevented from further moving downwardly with the 80 driver, whereas the driver, continuing in its downward movement, forces the leader and plug out of engagement with the spring-like gripping members 17, as will be hereinafter more fully set forth.

A base 22 supports the brush head 23 and which consists in this instance of a holder 24 in which are arranged the usual bristles 25, the said bristles, however, being substantially loose in the holder and adapted 90 to be rigidly secured therein by the plug 18. Therefore, when it is desired to complete the brush head 23 by rigidly securing the bristles in the holder, the holder with the bristles thereon is placed upon the base 95 22 and immediately beneath the supporting member 11 carried by the driver and holding the plug 18, with the leader 19 below it, said plug and leader being held in superposed relation to the brush body by the 100 spring-like gripping members 17. A downward pressure now exerted upon the driver advances the supporting member 11 and driver until the leader passes into the bristles of the brush body, and when the leader has been sufficiently advanced in the brush body the continued downward movement of the driver brings the projection 20 into engagement with the member 21, thus holding the supporting member so that the driver can further advance and slide through the supporting member, thereby pushing the leader 105 110

downwardly through the holder 24 and into the base 22, while the plug, following the path formed in the bristles by the leader, will be forced and pressed into the holder 24, thus securing the bristles rigidly in the holder.

When the downward pressure on the driver is released and the driver is moved upwardly a sufficient distance, the spring 16, 10 operating against the supporting member, will facilitate the downward sliding movement of the supporting member upon the driver so that the supporting member will again be in its initial position upon the 15 driver and ready for the next plug and leader. Thus, when it is desired to secure the bristles of a brush in a holder, it is only necessary to arrange the holder upon the base, with the bristles already arranged in 20 the holder and then load the supporting member with the plug and leader as mentioned, after which the downward pressure upon the driver will advance the leader and plug into the bristles of the brush so that 25 the leader will form or provide a path and the plug, coming immediately behind it, will be forced into the holder and secure the bristles therein.

As shown, it will be seen that the base 22 30 rests upon a surface or table 26 and the member 21 is preferably secured upon the table surface so that its upper angular end will lie in juxtaposition to the supporting member in the desired spaced relation to the projection 20 whereby, when the apparatus

is operated, the engagement of the projection with the angular end of the member 21 will hold the supporting member against further downward movement while the driver, continuing downwardly, forces the 40 leader and plug into the brush so that the plug will be forced into the holder to secure the bristles.

Having thus described my invention, I 45 claim:

1. In a plug inserting device for brush making, a driver, a stop pin on the driver, a sleeve surrounding and slidable on the driver and having a slot for the stop pin, a spring on the driver above the sleeve and 50 normally holding it against the stop pin, and spring jaws on the sleeve constructed to releasably hold a plug and a leader below the same.

2. In a plug inserting device for brush 55 making, a driver, a stop pin on the driver, a sleeve surrounding and slidable on the driver and having a slot for the stop pin, and a lateral projection adapted to engage a fixed support, a spring on the driver above 60 the sleeve and firmly holding it against the stop pin, and spring jaws on the sleeve constructed to releasably hold a plug and a leader below the same.

In testimony whereof I affix my signature 65 in presence of two witnesses.

ALEXANDER W. MOREY.
